UNITED STATES PATENT OFFICE.

WILLIAM D. THOMPSON, OF DETROIT, MICHIGAN, ASSIGNOR, BY MESNE ASSIGNMENTS, TO HUTCHINS CAR ROOFING COMPANY, OF DETROIT, MICHIGAN, A CORPORATION OF DELAWARE.

CAR-BODY CONSTRUCTION.

Application filed June 11, 1920. Serial No. 388,208.

The invention relates to car body constructions of that type employing metal plates, and consists in the novel construction of a trussed plate which can be developed 5 from a sheet metal blank without material drawing or flowing of the metal.

In the drawings:

Figure 1 is a perspective view of a plane sheet;

10 Figure 2 is a similar view of the sheet bent to place successive portions thereof in parallel spaced planes;

15 Figure 3 is a plan view of a blank from which a fashioned plate may be developed;

Figure 4 is a perspective view of the developed plate;

20 Figures 5 and 6 are views similar to Figures 3 and 4, showing a modified construction; and

Figure 7 is a view similar to Figure 6 of still another modification.

Heretofore metallic plates as used in car body constructions have been stiffened and strengthened by pressing or otherwise fashioning the same so as to form ribs or reinforcements. It is, however, desirable that the margins of the plates should be in a common plane so as to permit of attachment to each other and to the car frame and this 25 generally results in a form which cannot be developed from a flat sheet of metal without drawing or stretching of portions thereof. Inasmuch as any material drawing of the metal requires heat treatment and 30 powerful presses, there is an advantage in dispensing with the same. I have therefore devised a construction in which the body of a plate has portions thereof arranged in two planes with the marginal portions in a 35 single plane, said plate developed from a flat sheet without drawing of the metal.

The principle underlying my invention is 40 shown diagrammatically in Figures 1 to 4, in which A is a rectangular sheet metal blank having all portions thereof in a common plane. B in Figure 2 is the same sheet which has been bent to form a series of successive portions C, C', etc., which are alternately in different planes spaced from each 45 other and which are connected by transversely extending portions D. Such a form can be readily developed from the blank A by a simple bending operation and without any drawing or stretching of the metal, but

it will be noted that the margins on two 55 sides of the blank instead of being in a common plane, zig-zag between the two planes. By applying pressure the margins might be flattened down, but this would result in a distortion unless sufficient pressure is applied to upset or flow the metal into the common plane. If, on the other hand, sufficient metal is removed from the margin to correspond to the difference in length between the original sheet and the bent blank, 60 then the margin could be flattened down into a single plane without distortion.

As shown in Figures 3 and 4, the blank is so cut that the marginal portions thereof 65 may be bent into a common plane perpendicular to the two planes of the body portion. This is accomplished by removing a portion E between portions F and G in the margin of the blank, the amount removed and the contour of the remaining portions 70 being such that their edges will come together when the blank is bent. These adjoining edges may then be secured by soldering, brazing, welding, or other suitable means.

As shown in Figures 5 and 6, the marginal portion has a series of gores H cut 75 therein, which, when the blank is fashioned about the lines I, J, K and L, will close in, forming a flange at right angles to the two planes and a tapering portion from the upper plane to the lower. The meeting edges are soldered, welded, or otherwise secured, as in the construction previously described. In Figure 6 the gore is so arranged that the meeting edges will be central of the upper plane portion, while in the modification shown in Figure 7, these meeting edges are in the lower plane portion.

The constructions described can all be 80 cheaply manufactured, due to the fact that the cost of press work is greatly reduced over constructions in which the metal must be drawn. The fact that a portion of the 100 metal is removed from the border portion of the sheet does away with the necessity of upsetting or flowing the metal and this permits of performing the fashioning operation with relatively light presses. Also, 105 the work may, if desired, be performed upon the cold metal, which would be practically impossible if there was any consid-

erable drawing or upsetting required. The zig-zag sheet can be rolled at the mill and where this is done, the only operations necessary are the goring and pressing of the end portions of the sheets.

5 What I claim as my invention is:

1. A fashioned metal plate comprising successive portions in the body thereof arranged in separated parallel planes, and a 10 marginal portion in a common plane, said margin having closed cut out portions which compensate for the difference in length of the fashioned and unfashioned portions.

2. A fashioned metal plate developed

from a plane sheet having alternate portions in the body thereof arranged in spaced parallel planes, a marginal portion in a common plane bent at an angle to one of said spaced planes and connecting with the other of said spaced planes by an obliquely 15 extending portion, the metal of the blank having a gore therein, the opposite edges of which are brought together in the fashioned blank and sealed.

10 In testimony whereof I affix my signature.

WILLIAM D. THOMPSON.
